United States Patent Office

Des. 225,974

Patented Jan. 16, 1973

225,974

BOTTLE

William Barth, Columbus, Ga., assignor to Royal Crown
Cola Co., Columbus, Ga.

Filed May 6, 1971, Ser. No. 141,085

Term of patent 14 years

Int. Cl. D9—01

U.S. Cl. D9—100

FIG. 1

FIG. 2

FIG. 3

FIG. 1 is an elevational view of a bottle showing my new design, the opposite side being the same in appearance as the side shown;

FIG. 2 is a top plan view; and

FIG. 3 is a bottom plan view thereof.

I claim:

The ornamental design for a bottle, as shown and described.
